UNITED STATES PATENT OFFICE.

WILLIAM ROY GREEN, OF TRINIDAD, COLORADO.

LEVEL.

1,198,721.

Specification of Letters Patent. Patented Sept. 19, 1916.

Application filed August 19, 1915. Serial No. 46,324.

To all whom it may concern:

Be it known that I, WILLIAM ROY GREEN, a citizen of the United States, residing at Trinidad, in the county of Las Animas and 5 State of Colorado, have invented new and useful Improvements in Levels, of which the following is a specification.

This invention relates to levels, and has for its primary object to provide a level of 10 simple construction in which the vital parts may be readily removed or assembled for obvious reasons.

One of the objects of the invention is to construct certain portions of the level and 15 form the same with graduation marks whereby the latter may be viewed by the observer in various positions.

Another object of the invention is the arrangement between the sets of graduation 20 marks and the hands, the latter being so shaped as to simultaneously coöperate with the two sets of graduation marks.

A still further object of the invention is the novel manner in which the side members 25 are secured together and the members as a unit respectively held against displacement within the body by means of the co-operation between the annularly disposed peripheral edge portion of the members and 30 the wall of the opening.

With these and other objects in view the invention consists in the features of construction and the combination and arrangement of parts hereinafter described and 35 claimed, reference being had to the accompanying drawing, in which—

Figure 1 is a side elevation of the level; Fig. 2 is a vertical sectional view on the line 2—2 of Fig. 1; and Figs. 3 and 4 are 40 detail sections.

Referring to the drawing the numeral 1 designates the body of the level, which is shown as formed with a circular opening 2, the wall 3 of which is triangular shape in 45 cross section as clearly shown in Fig. 2 of the drawing. Each of the circular side members 4 and 5 are depressed in the course of manufacture at the point 6 to form annular grooves 7, the concentric walls 8 and 50 9 of which are arranged at an angle to each other. The walls 9 of the side members tightly abut the walls 3 of the opening and from this arrangement it will be seen that lateral movement of the side members is 55 prevented when the screws 10 tightly draw

the bottom walls of the grooves together. The walls 8 are provided with an annular series of graduation marks 11, while the flat body portions 12 of the side members are each provided with an annular series of 60 graduation marks 13. The hands 14, two in number, are so shaped and arranged as to simultaneously coöperate with the graduation marks 11 and 13, and to accomplish this the end portions of the hands are bent at 65 an angle so as to overlie the walls 9. The hands 14 are mounted on the squared ends 15 of the shaft 16 that is journaled in the side members. For preventing displacement of the hands from the shaft I mount 70 in each end of the shaft a screw 17, the head of which abuts a washer 18 that in turn abuts the adjacent surface of an associated hand.

18 designates a weight moving between 75 the side members and which can be either formed integral with the shaft or secured thereto in any suitable manner. Circular glasses 19 have their peripheral edge portions abutting the edges of the circular side 80 members with the result that the same are spaced a sufficient distance from the hand to allow free movement of the latter. For securely holding the glasses in position I provide rings 20 abutting the outer surfaces of the glasses and through which pass screws 21 which in turn have threaded engagement with the edge portions of the side members.

From the foregoing description it will 90 be seen that I provide a simple device in which the parts are effectively assembled or displaced by simply removing a small number of screws.

A very important feature of my invention which should be borne in mind is the relative arrangement between the graduation marks, the hands and remaining portion of the side members so that the graduation marks may be plainly seen from any 95 angle in which the observer may be. By tightening up the screws 10 it will be seen that the side members are brought into tight engagement with each other for preventing the ingress of moisture to the space in which the weight 18 works and at the same time the inclined walls 8 are brought into tight contact with the wall of the opening for the purpose previously described.

If found advantageous in practice the 110

degree marks may have printed adjacent thereto the number of inches incline to the foot as clearly shown in Fig. 1 of the drawing.

5 Having thus described my invention, I claim:

1. In a level, a body having a circular opening, a pair of circular side members each having a flat body portion provided 10 with graduation marks, inclined peripheral edge portions and an intermediate portion arranged between the edge portion and the body portion and at an angle thereto, said intermediate portion being provided with 15 graduation marks, a weighted shaft journaled in said side members, hands detachably secured to the ends of said shaft, each of said hands having its end portions bent at an angle so as to coöperate with the intermediate portion of its associated side member.
2. In a level, a body having an opening formed by two walls arranged at an angle to each other, side members having angularly arranged peripheral edge portions 25 engaging the walls of the opening, screws for detachably securing said members together, and weighted rotatable means associated

with said side members for giving visible indication.

3. In a level, a body having an opening, formed by two walls arranged at an angle to each other, a pair of side members, each being stamped to have an annular groove, the concentric walls of which are arranged 35 at an angle to each other and the inner of which is provided with graduation marks, while the outer wall abuts one of said first mentioned walls, a shaft journaled in said side members, each of said side members 40 being provided with an annular series of graduation marks arranged concentrically of said shaft, and hands secured to the ends of said shaft and having their end portions bent at an angle, said hands being adapted 45 to simultaneously coöperate with the first and second mentioned graduation marks, and a glass plate for each member having the edge portion secured to the other concentric wall formed by said groove.

50 In testimony whereof I affix my signature in presence of a witness.

WILLIAM ROY GREEN.

Witness:

BENNETT S. JONES.
